INVENTOR

Robert Smith Looker

UNITED STATES PATENT OFFICE.

ROBERT SMITH LOOKER, OF SPRINGFIELD, OHIO.

SEWING-MACHINE.

SPECIFICATION forming part of Letters Patent No 361,427, dated April 19, 1887.

Application filed December 7, 1883. Renewed August 4, 1886. Serial No. 210,031. (No model.)

To all whom it may concern:

Be it known that I, ROBERT SMITH LOOKER, of Springfield, in the county of Clark and State of Ohio, have invented a new and useful 5 Improvement in Sewing-Machines, of which the following is a full, clear, and exact description, reference being had to the accompanying drawings, making part of this specification.

My invention relates to a hinged or swinging face-plate for sewing-machines; and it consists in the peculiar construction and arrangement of the parts, which will be more fully hereinafter described, and definitely pointed out in the claims.

15 The object of my invention is to provide a face-plate in combination with the head of the arm, which may be first opened and swung back in a horizontal plane and then turned and raised in a vertical plane, together with 20 the parts contained therein.

A further object of my invention is to so construct the face-plate that it may be swung away from the bed-plate and leave a clear, open, unobstructed space which will admit of 25 free access to the feed and shuttle mechanism below the bed-plate, and whereby cumbersome articles to be operated upon may be readily and easily placed upon the bed-plate under the needle and presser-foot bars, and 30 also to adjust the needle and rearrange any of the parts in the face-plate which may have become disarranged.

I attain these objects by the mechanism illustrated in the accompanying drawings, wherein 35 like letters of reference indicate similar parts in the several views, and in which—

Figure 1 is a perspective view of the head of the arm and the face-plate, showing the face-plate opened and swung in a horizontal 40 plane, or its first position. Fig. 2 is a like view showing the face-plate swung in a vertical plane, or its second position. Fig. 3 is a detail perspective view of the universal hinged joint.

45 The hinge I, for connecting the arm-head H with the face-plate, is formed with a leaf, I', and an ear or hub, I², formed with a smoothly-bored bearing, through which the shank or journal of a stud-bolt, I³, passes, and within 50 which it freely turns. The leaf I' is screwed fast to the farther side of the arm-head H by short

screws passing through holes i i, and the stud-bolt I³ passes freely through the hub I² and screws into the adjoining side of the face-plate H', by which means the face-plate may be first 55 swung in a horizontal plane to the position shown in Fig. 1, and then turned in a vertical plane upon the stud-bolt to the position shown in Fig. 2, in which position the needle may be conveniently adjusted and threaded, and 60 the face-plate may be in position to afford access to the interior parts, which consist in this instance of the needle-bar K, presser-foot bar L, and take-up lever M. The needle-bar is made to slide in ways which will permit its 65 outer surface to be flush with the inner surface of the face-plate, and is held in such a position as to prevent it from dropping out of its seat by a half-headed stud-bolt, k, that screws into the face-plate. By giving the 70 stud-bolt a half-turn the half-head will be placed from over the needle-bar and allow it to be removed when desired.

When the hinged face-plate is restored to its closed position upon the fixed arm-head, it 75 may be held securely in said closed and working position by a hook, L, or other suitable locking device.

The above construction having been carefully followed out, the operation of my improved device is as follows: The loop or hook, or any other suitable fastening which may secure the hinged face-plate to the head of the arm, is unfastened from an eye on the movable face-plate, and the said face-plate is then swung 80 in a horizontal plane away from the feed and needle-hole plate, carrying with it the presser-foot and needle bars. The face-plate can now be turned in a raised or vertical plane by taking hold of the same and turning it on the 85 pivotal portion of the hinge. The pivotal portion of the hinge now acts as an axis, and the face-plate can be turned in a circle, if necessary, or to any required distance. To cause the face-plate to resume its normal position, it is 90 turned back until it is in a vertical line with the head of the arm, and then swung in its horizontal plane, and engages with the pins on the head of the arm, and the mechanism will assume its normal position with relation 95 to the feed and needle-hole plate.

It is obvious that many minor details of con-

struction could be substituted for those shown and described without in the least departing from the nature and principle of my invention.

I claim as my invention, and desire to secure by Letters Patent—

1. In a sewing-machine, the combination, with a fixed arm, of a face-plate hinged thereto and adapted to be swung in a horizontal and also in a vertical plane, substantially as described, whereby the face-plate may be placed in a horizontal position with its inner face up-
permost.

2. In a sewing-machine, the combination, with the hinged face-plate, of a needle-bar fitted in ways upon the inner face thereof, and a locking device secured to the face-plate to hold the needle-bar in its ways or permit it to be removed therefrom, substantially as described.

3. In a sewing-machine, the combination, with the face-plate and the head of the arm, of a pivotal hinge having a leaf, and an ear car-

rying a pivot-screw, the said parts being secured to the face-plate and the head of the arm, whereby the face-plate may swing in a horizontal and then in a vertical plane, substantially as described.

4. In a sewing-machine, the combination of the head of the arm H, face-plate H', pivotal hinge I, having a leaf, I', and an ear, I², carrying a pivot, I³, a locking device for clamping the needle-bar, as k, and means for securing the face-plate to the head of the arm, all arranged in such manner as to permit the face-plate to be turned first in a horizontal plane and then in a vertical plane, substantially as described.

In testimony whereof I have hereunto set my hand this 27th day of November, A. D. 1883.

ROBERT SMITH LOOKER.
